CLAIM

The ornamental design for a guidewire, as shown and described herein.

DESCRIPTION

FIG. 1 is a perspective view of a first embodiment of a guidewire showing our new design;

FIG. 2 is an enlarged view of the first embodiment;

FIG. 3 is an enlarged view the first embodiment;

FIG. 4 is a left side view of the first embodiment;

FIG. 5 is a right side view of the first embodiment;

FIG. 6 is a front view of the first embodiment;

FIG. 7 is a rear view of the first embodiment;

FIG. 8 is a top view showing the distal end of the first embodiment;

FIG. 9 is a bottom view showing the proximal end of the first embodiment;

FIG. 10 is a perspective view of a second embodiment of a guidewire showing our new design;

FIG. 11 is an enlarged view of the second embodiment;

FIG. 12 is an enlarged view of the second embodiment;

FIG. 13 is a left side view of the second embodiment;

FIG. 14 is a right side view of the second embodiment;

FIG. 15 is a front view of the second embodiment;

FIG. 16 is a rear view of the second embodiment;

FIG. 17 is a top view showing the distal end of the second embodiment; and,

FIG. 18 is a bottom view showing the proximal end of the second embodiment.

The dot-dash broken lines and evenly spaced broken lines immediately adjacent to the shaded areas represent the bounds of the claimed design, and form no part of the claimed design. All other evenly spaced broken lines are directed to environment. The dot-dot-dash broken lines encircling portions of the claimed design in FIGS. 2 & 3 and 11 & 12 that are illustrated in enlargements in FIGS. 1 and 10, respectively, form no part of the claimed design. In addition, the broken away bracket symbols with dotted broken lines in the drawings indicate that any portion of the article beyond what is shown forms no part of the claimed design.

1 Claim, 10 Drawing Sheets
